United States Patent Office.

JAMES McCARTHY, OF NEW YORK, N. Y.

Letters Patent No. 77,503. dated May 5, 1868.

IMPROVEMENT IN EXTENSION-PIPE COUPLING.

The Schedule referred to in these Letters Patent and making part of the same.

TO ALL WHOM IT MAY CONCERN:

Be it known that I, JAMES McCARTHY, of the city, county, and State of New York, have invented a new and improved Extension-Pipe Coupling; and I do hereby declare that the following is a full, clear, and exact description thereof, which will enable others skilled in the art to make and use the same, reference being had to the accompanying drawings, forming part of this specification, in which—

Figure 1 represents a longitudinal section of my improved pipe-coupling.

Figure 2 is an end view of the same.

Similar letters of reference indicate corresponding parts.

This invention relates to a new pipe-coupling, which is so arranged that the ends of pipes that are a greater or less distance apart from each other can be connected by the same. Its object is to take the strain from the pipes, and to make up small spaces which may be left between the ends of the pipes.

The invention consists in the use of two pieces of pipe, of which one screws into the other, so that the whole length may be increased or diminished at will. At the outer end of each piece is a screw-thread or other means of connecting it to the pipe.

The invention is applicable to steam, gas, water, and other pipes.

A represents a tubular piece, which is provided with a screw-thread, *a*, around its surface, the same extending from its inner end almost to the outer end.

B is a tubular piece, having a screw-thread, *b*, on its inside, which corresponds to that on A, so that the two pieces can be screwed together, as shown.

In the outer end of each piece, A and B, is an internal screw-thread, or its equivalent, by which each piece can be secured to a piece of pipe, as shown by red lines in fig. 1. It will be seen that, by this arrangement, the coupling A B can be made longer or shorter at will.

C is a jam-nut, which has a conical end corresponding to a similar depression or concave in the inner end of B. By means of this nut the pieces can, at all times, be firmly secured in any position.

By having one or more branches on the piece A or B, three or more pipes may be connected by this coupling.

Having thus described my invention, what I claim as new, and desire to secure by Letters Patent, is—

1. An extension-pipe coupling, made by connecting the tubular pieces A and B, substantially in the manner set forth.

2. The above in combination with the jam-nut C, made as herein shown and described.

JAMES McCARTHY.
